FLEXIBLE AMMUNITION MACHINE GUN
FEED

Carleton R. Elliott, Dayton, Ohio

Application June 13, 1942, Serial No. 446,902

4 Claims. (Cl. 89—33)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to improvements in machine gun feeding mechanism particularly adapted for use with a machine gun mounted for elevational movement such as employed in aircraft.

Heretofore it has been the practice to feed ammunition to a machine gun—of the type 10 mounted for elevational movement in a turret or the like on an aircraft—from a shallow ammunition container removably secured to the gun, the container incorporating therewith a curved chute for guiding the ammunition from the container to the feedway of the gun. To permit ease of handling, each container holds only a small quantity of ammunition which must be replaced by a full container as soon as the ammunition is exhausted, which also requires the rethreading of the ammunition belt into the feed mechanism of the gun. Further the mass added to the gun by mounting the ammunition container and feed chute thereon has a detrimental effect on the firing of the gun since it adds considerably to the 15 inertia of the gun frame, which when taken with the resilient characteristics of the recoil absorbing mechanism, limits the possible rate of fire.

To overcome the difficulties encountered with the prior art feeding mechanisms, the present invention uses a single ammunition container mounted separate from the gun and adapted to contain all of the ammunition intended to be fired from a single gun in a single belt preferably of the type in which the cartridges are interconnected by links. The ammunition belt after being withdrawn from the container is preferably passed over a guide such as a rotatable toothed sprocket mounted separate from the gun, the ammunition belt then being passed over a second 20 guiding means of a similar character mounted independent of the gun and spaced laterally from the first guiding means. The ammunition belt passes from the second guiding means into the feedway of the gun.

The second guiding means is so mounted that it is free to rotate about an axis parallel with the elevation axis of the gun and also to swivel about an axis at right angles thereto so that as the gun is elevated or depressed from a level position the second guide will rotate in a corresponding direction through approximately one half the angle of rotation of the gun and will also swivel transversely so that the ammunition belt can twist without binding and enter the feedway of

the gun in alignment therewith. By this arrangement the gun is relieved of the major portion of the weight of the ammunition and thus reduces the inertia of the gun which allows a greater rate of fire thereof, and feeding the ammunition from a single container eliminates changing ammunition boxes and rethreading the ammunition belt and allows clear access to the gun for clearing a jam if the same should occur.

15 In some instances where space is limited the swivelled ammunition belt guide may be employed as the sole guide interposed between the ammunition container and the feedway of the gun and may be supported by a ball type universal joint to allow angular movement of the guiding means in any plane and also to rotate about an axis parallel with the elevation axis of the associated machine gun.

It is therefore an object of the invention to 20 provide, in an ammunition feed for a machine gun mounted for elevational movement, an ammunition container supported separate from the gun and a guiding means for a belt of ammunition withdrawn from the container and so mounted as to be angularly rotatable about an axis parallel with the axis of elevation of the gun.

A further object of the invention is the provision, in an ammunition belt feed for a machine gun mounted for elevational movement, of guiding means for the ammunition belt which will support a substantial portion of the weight thereof and the guiding means being mounted independent of the gun, the mounting being constructed and arranged to permit the guiding means to swivel at least about two axes at right angles to each other and one of the axes being parallel to the elevational axis of the gun.

A further object of the invention is the provision in an ammunition feed for a machine gun mounted for elevational movement, of an ammunition container mounted separate from the gun, of a first roller guiding means mounted separate from the gun and adapted to guide an ammunition belt thereover to a second roller guiding means spaced laterally therefrom and over which the ammunition belt passes to the feedway of the machine gun, each of the guiding means being supported separate from the gun and the second guiding means being supported in a swivel mounting which permits angular movement thereof about axes respectively parallel and perpendicular to the axis of elevational movement of the gun.

Other objects and features of the invention not 55 specifically enumerated above will appear by ref-

erence to the detailed description hereinafter given and to the appended drawing in which:

Fig. 1 is a view taken in perspective illustrating the invention, and;

Fig. 2 is a perspective view illustrating the detailed construction of one form of swivelled guide such as illustrated in Fig. 1, and;

Fig. 3 is a view similar to Fig. 2, illustrating a modified form of swivel mounting for the ammunition guide of Fig. 1.

Referring now to Fig. 1 the reference numeral 1 indicates a conventional type of machine gun such as employed on military aircraft and having an ammunition feedway 1a and mounting lugs 2 for securing the gun frame to shock absorbing springs or equivalent recoil absorbers such as indicated at 3 and 4. The recoil springs 3 and 4 are secured to an arm 5 having integrally formed therewith a gear sector 6, adapted to cooperate with a power drive, not shown, to cause elevational movement of the gun. The arm 5 is provided with a bearing boss 7 on either side thereof which serves to mount the arm 5 for rotation about the axis x-x of the spindle 8 which is supported in a fork 9 formed as an integral part of the column 10 which is secured to mounting structure (not shown) forming part of a rotatable gun turret or the like. Though only a single gun is shown supported in the above described mounting, a similar gun (not shown) is secured to the other ends of the springs 3 and 4.

The gun 1 is supplied with ammunition from a single container 12 which is supported independent of the gun and is of a size sufficient to contain all of the ammunition to be fired by the gun 1, the ammunition being arranged in a belt as generally indicated at 14 in which the individual cartridges 15 are interconnected by removable links 16 of well known construction, to thereby form a flexible ammunition belt well known in the art. The container 12 is preferably positioned below and close to the plane of the gun and the ammunition belt 14 after withdrawal from the container passes through a roller guide generally indicated by the reference character 18, which includes an attachment member 19 which is secured to the turret framework (not shown). The detail construction of the roller guide 18 is the same, except in the means of support, as a second roller guide 20 now to be described.

The ammunition belt 14 after passing over the roller guide 18 is passed through a second roller guide generally indicated by the reference numeral 20 which is spaced laterally from and slightly above the guide 18. The detail construction of the guide 20 is illustrated in Fig. 2 and as there illustrated is seen to comprise a pair of spaced end plates 21 secured in assembled relation by upper and lower plates 22 welded thereto, the latter having edges smoothly rounded for guidance of the ammunition belt and a mounting plate 23 is welded to the side plates to which the mounting structure is applied. The side plates 21 are each provided with a bearing sleeve 24 threaded therein and adjustably secured by a lock nut 25, a spindle 26 being rotatably mounted in the bearing sleeves 24. The spindle has mounted thereon in spaced relation, a pair of sprocket toothed guides 27, for supporting the case of the cartridges and a roller 28 adapted to support the nose portion thereof. One of the end plates 21 is provided with radially extending guide rollers 30 which engage the base of the cartridge cases in guiding relation. The guide 20 thus far described is identical in construction with the guide 18, the latter being,

however, provided with a welded on attaching means 19 previously noted.

The guide 20 is provided with a mounting means comprising a flange 31 welded to the back plate 23 and provided with an integrally formed rearwardly extending bearing spindle 32, which is rotatably journaled in a bearing hub 33 and the spindle being restrained against axial movement by means of a thrust washer 34 and retaining nut 35. The hub 33 is provided with integrally formed bearing extensions 36 into which vertical bearing pins 37 extend, the pins 37 being removably secured to a U-shaped bracket 38 which is welded to a mounting flange member 39, which in turn may be bolted to a structural member such as indicated by the reference numeral 40, forming for example a part of the gun turret (not shown). By means of the above described pivotal mounting structure the guide 20 may rotate about the axis of spindle 32 indicated as y-y in Figs. 1 and 2 and also swivel about the vertical axis of bearing pins 37 indicated as axis z-z in Figs. 1 and 2.

Operation

The operation of the novel ammunition guiding means of Fig. 1 is as follows; an end of the ammunition belt 14 is withdrawn from the container 12 and threaded through guides 18 and 20 into the feedway 1a of the machine gun 1. If then the gun elevation is changed before or during firing, the gun will be rotated about axis x-x of Fig. 1, which will create a torque or twisting moment on the cartridge belt between the gun feedway 1a and the guide 20 which torque will cause the guide 20 to rotate about the axis y-y which in turn will cause a twist in the ammunition belt 14 between the guide 20 and the fixed guide 18 so that the total angular twist of the belt will be distributed over the whole length of the same between the gun feedway 1a and the guide 18. The guide 20 will rotate about axis y-y through an angle equal approximately to one half the angular change in elevation of the gun 1. As the angle of elevation of the gun is changed, the belt 14 is rotated in a horizontal plane to some extent and the provision for pivotal movement of the guide 20 about the axis z-z ensures proper guidance without binding, for this condition and this provision for pivotal movement also cares for the change in belt alignment due to reciprocating movement of the gun caused by recoil. By using rollers in the guides 18 and 20 and laterally spacing the guide 20 from guide 18, as illustrated in Fig. 1, the major portion of the weight of the ammunition belt is supported independent of the gun, thus not adding to its mass and the ammunition belt is subject to rolling friction only, in passing from the container to the gun feedway.

It is, of course, to be understood that where space limitations prevent the lateral spacing arrangement of the guide means as illustrated in Fig. 1, the stationary guide 18 may be eliminated and the ammunition belt 14 guided solely by a pivotally mounted guide such as the guide 20 of Fig. 1.

Where there is the possibility of considerable movement of the ammunition belt in a vertical plane, a full universal mounting for the guide 20 may be provided as illustrated in Fig. 3, in which the back plate 23 of the guide 20 has secured thereto as by welding, a flange 42, which has integrally formed therewith a rearwardly extending shouldered stem 43 on which is secured a ball 44 which serves as a bearing, the ball being retained

by a sleeve 45, lock washer 46 and a nut 47 secured on the threaded outer end portion 48 of the stem 43. The bearing ball 44 is journaled in a spherical bearing seat 50 formed in the separable support members 51 and 52 which are retained in assembled relation by cap screws such as 53, between which members the ball 44 has universal movement. The support member 51 is provided with a mounting flange 54 by which the assembly is secured to a structural member of the gun turret such as the member 40 of Fig. 2. The provision of the full universal mounting of Fig. 3 allows the guide 20 to rotate about an axis parallel with the elevation axis of the gun and also to move simultaneously in the horizontal and vertical planes. The operation of the guide is otherwise identical with that as above described with reference to Fig. 1.

While roller guides have been disclosed in the drawing and are preferred because they minimize friction, it is to be understood that guides of the type in which the ammunition belt slides therethrough may be employed, provided that at least one of the guides is so supported that it is capable, at least, of angular motion about an axis parallel with the elevational axis of the gun.

While preferred forms of the invention have been illustrated and described, it will be apparent to those skilled in the art that other modifications and variations may be made therein falling within the scope of the invention as defined by the appended claims.

I claim:

1. The combination with a machine gun mounted for elevational orientation, an ammunition belt feed mechanism comprising a belt guide support spaced laterally a substantial distance from the gun and fixed relative to gun elevation, a belt guide from which the belt is fed to the gun, means mounting said guide on said support, a second belt guide below the first laterally spaced therefrom and mounted independently of the gun and constructed and arranged to guide the belt to the first mentioned guide, said mounting means of the first mentioned guide being so constructed and arranged as to allow said first guide, through the instrumentality of the belt, to be rotated upon an axis parallel to the elevational axis of the gun and to swivel upon an axis at right angles to

said elevational axis in response to the forces on said guide occasioned by elevation of the gun.

2. In combination with a machine gun mounted for elevational orientation, an ammunition belt feed mechanism comprising a belt guide support spaced laterally a substantial distance from the gun and fixed relative to gun elevation, a belt guide from which the belt passes to the gun, means mounting said guide on said support, the mounting for said guide being so constructed and arranged as to allow said guide, through the instrumentality of the belt, to be rotated upon an axis parallel to the elevational axis of the gun and to swivel upon an axis at right angles to said elevational axis in response to the forces on said guide occasioned by elevation of the gun.

3. In combination with a machine gun mounted for elevational orientation, an ammunition belt feed mechanism comprising a belt guide support spaced laterally a substantial distance from the gun and fixed relative to gun elevation, a belt guide from which the belt is guided to the gun, means mounting said guide on said support including a universal joint allowing said guide, through the instrumentality of the belt, to be rotated upon an axis parallel to the elevational axis of the gun and to swivel upon an axis at right angles to said elevational axis in response to the forces on said guide occasioned by elevation of the gun.

4. In combination with a machine gun mounted for elevational orientation, an ammunition belt feed mechanism comprising a belt guide support spaced laterally a substantial distance from the gun and fixed relative to gun elevation, a sprocket tooth rotatable belt guide from which the belt passes to the gun, means mounting said guide on said support, a second guide below the first and spaced laterally a substantial distance therefrom and adapted to guide the belt to the first mentioned guide, the mounting of the first mentioned guide including a universal joint allowing said guide, through the instrumentality of the belt, to be rotated upon an axis parallel to the elevational axis of the gun and to swivel upon an axis at right angles to said elevational axis in response to the forces on said guide occasioned by elevation of the gun.

CARLETON R. ELLIOTT.
